SHEET-FEEDING MECHANISM.

1,412,812.

Specification of Letters Patent. Patented Apr. 11, 1922.

Application filed April 21, 1920. Serial No. 375,553.

To all whom it may concern:

Be it known that I, JOSEPH WHITE, a citizen of the United States, residing at Middlesex, county of Middlesex, State of New Jersey, have invented certain new and useful Improvements in Sheet-Feeding Mechanisms, of which the following is a specification.

My present invention relates to sheet-feeding apparatus in which a pile of sheets is presented to sheet-handling devices operating on the top sheet thereof.

As is well understood, in sheet-feeding devices as now in use, sheet-handling mechanisms of various types and designs are arranged to pick up and remove the sheets one by one from the top of a pile. These mechanisms ordinarily have a plurality of separate devices operating on a certain portion of the sheet. Ordinarily, the pile is supported in such fashion as to be raised from time to time to maintain the top thereof at approximately the same elevation.

While, theoretically, the top of the pile is a level plane, it is found in practice that there is usually no such condition. Due to various causes, the top of a sheet pile usually has small hills and valleys and, moreover, the size and locations of these hills and valleys will change as the sheets are withdrawn from the pile and the pile decreases in height. Ordinarily, the sheet-handling devices are designed so as to cooperate best with the topmost sheet when the vertical relation between the sheet and the device falls within certain defined limits. Consequently, if, due to the formation of a hill or a valley beneath one of these operating devices, this vertical relation is disturbed, it has been heretofore necessary to stop the machine in order to adjust the height of the operating device. In some instances, the same result has been procured by driving wedges or the like into the sides of the pile so as to raise a portion thereof. This latter arrangement is obviously very crude and is not always successful. Moreover, the driving of such wedges not only affects the sheets above the wedge, but may also affect them below it, so that the removal of these wedges when they have reached nearly the top of the pile discloses a condition in the

lower sheets which in turn must be corrected in some fashion by wedges. Furthermore, the presence of these wedges requires observation on the part of the attendant to insure their withdrawal before the sheets above them have been entirely removed.

One of the objects of my invention is to provide mechanism by which any limited portion of the pile and the sheet-handling device cooperating with such portion, may be brought into and maintained in correct operative relation, this adjustment being arranged so that it may be made and maintained without regard to the relation between any of the other devices and the portion of the sheet with which they cooperate.

Another object of my invention is to provide devices by which any predetermined portion of the pile may be raised without affecting the remaining portions by mechanism operated from beneath the pile.

With these and other objects in view, my invention consists in the arrangements and constructions herein described and more particularly pointed out in the appended claims.

In the drawings, Figure 1 is a side elevation of an illustrative embodiment of one form of my invention shown as applied to a paper-feeding mechanism for feeding sheets from the top of sheet pile to a printing press; Fig. 2 is a plan view of the pile support shown in Figure 1; Fig. 3 is a partial elevation, partly in section, of a portion of an illustrative form of mechanism applicable to the arrangement shown in Figure 1, and Figs. 4 and 5 are elevations, each partly in section, of sheet-handling devices adapted to cooperate with the pile-handling devices shown in Fig. 1.

In the drawings the same reference characters in the different views refer to the same parts.

In the illustrative embodiment of my invention shown in Figure 1, 10 is the frame of a printing press having a cylinder 11 to which the sheets are carried by tapes 12. At the left of the figure is shown, in more or less diagrammatic fashion, one form of sheet-handling mechanism which I have selected for purposes of illustration. It will be understood, however, that any other sheet-handling mechanism may be used.

In the sheet-handling mechanism illustrated, 15 is a section sheet separator adapted to contact with the topmost sheet and lift it in the well-known manner, the separator being connected through the hose 16 with a pipe 17 leading to any suitable suction pump. The separator 15 is mounted on the head 18 and is raised and lowered by a cam 19 on a shaft 20, a cam lever 21 operating through a lifting lever 22 to raise the separator 15 from time to time and to permit it to drop again. It will be understood that any suitable form of buckling device may be associated with the separator 15.

15 23 is a feeding-off roller supported in a lever 24 pivoted at 25 in the end of a lever 26 connected to the shaft 27, this shaft being controlled by a cam 28 on the shaft 20 to move the lever 26 forward to feed off a sheet, a spring 29 being provided to return the lever 26 to original position.

The sheet separator and feeding-off devices are of a well-known type, and further description thereof will be unnecessary to those skilled in the art. It will be understood, however, that ordinarily, only two of the separators 15 are provided, each cooperating with one of the rear corners of the topmost sheet. Three or more of the feeding-off rollers 23 are ordinarily provided, each acting on a portion of the front of the topmost sheet.

In the arrangement illustrated in Figure 1, the pile of sheets to be fed is supported on a board 30 provided with cross cleats or braces 31, which, in the form shown, rest in turn on channel beams 32, 33 extending across the machine, the ends of these beams in turn being supported by lifting bars 34, one of which is provided at each side of the machine. The ends of the lifting bars are carried in loops 35 each attached to the end of cables 36 which pass over drums 37 attached to a shaft 38, this shaft having on its end a drum 39 over which passes a cable 40, the lower end of which, in the mechanism illustrated, is connected to any suitable entire-pile-lifting device in the manner well understood in the art. The pile support so far described is that of an arrangement old in the art and further description thereof will be unnecessary. It will be understood, however, that the device which controls the cable 40, may be connected to any of the well-known forms of pile detectors arranged to contact with any selected portion of the pile and connected to the mechanism for operating the cable 40, so that, as the top of the pile is lowered through the feeding-off of the successive sheets, the cable 40 will be pulled down from time to time to rotate the shaft 38 so as to pull up on the cables 36 to raise the entire pile until the top thereof beneath the pile detector is again at the pre-determined height.

As has been pointed out above, the sheet-handling devices are ordinarily set so as to cooperate with the top of the pile as if that top were of a uniform level. If, therefore, as the pile is first built up or as it develops 70 after a number of sheets have been fed off, some parts thereof are higher than others, then, obviously, the proper relation between the sheet-handling devices and the parts of the sheet with which they cooperate, will not 75 be had or be maintained. In the arrangement illustrated, I overcome this difficulty by providing, at a plurality of points, a number of sheet supports which are auxiliary to the board 30, each support being of a 80 relatively small area and preferably located approximately beneath the operative position of one of the devices of the sheet-handling mechanism. In the arrangement shown, I have provided at the rear of the pile a pair 85 of round plates or supports 42 having a stem 43 passing through a suitable opening in the board 30, which latter is preferably recessed so that the plate 42 may sink beneath the surface of the board. Mounted in 90 the channel beam 32, as shown best in Figure 3, is a vertically movable rod 44 provided with a screw portion 45 on which is a nut 46, the outer surface of this being formed as a worm wheel which engages a worm 47 95 on a cross shaft 48 supported in bearings on the channel beam. Also attached to the channel beam 32 is a bracket 49 containing a solenoid 50 and a movable core 51 which is normally held in the position shown in Figure 3 by a spring 52. On the opposite end of the core 51 is a rod 53, the end of which is formed as a pawl adapted to engage a ratchet wheel 54 attached to the shaft 48. The shaft 48, as shown best in Figure 2, is carried out 10 beyond the end of the board 30 and is provided with a hand wheel 55 by which the shaft may be rotated independently of the pawl 53 in either direction. The normal position of the pawl 53 is such that it is 11 clear of the ratchet teeth, as shown in Figure 3.

The plate 42 at the opposite end of the board is provided with mechanism similar to that just described, though, if desired and 11 as indeed will be required at the front of the board, as will be hereinafter explained, the position of the screw 45 and the nut 46 and shaft 48 will be elevated as shown in Figure 3, so as to prevent any interference between 12 the two mechanisms at either side of the board, and so that, if desired, each shaft 48 may be extended entirely across the board so that each of them may be operated from the same side of the board by means of 12 suitable hand wheels 55.

On the front of the board, as shown in Figure 2, I have provided three independent supports 421 which, in this instance, are shown as rectangular and as three in num- 13

ber. The mechanism for elevating these plates is the same as that just described. By arranging the shaft 48 on different planes, as heretofore explained, and as shown in Figure 3, the center support may be operated by hand from the side of the board 30 without interference with the other mechanisms.

Preferably, each of the sheet-handling devices is provided with an arrangement by which the auxiliary support immediately below it will be controlled so that the portion of the topmost sheet with which it cooperates, will be maintained in proper working relation with such device. To that end, and as one form of such mechanism, I have shown the sheet feeding-off devices 23 as provided with an adjustable screw 55, the end of which, at each stroke of the feeding-off device, passes to a point where it will contact with a member 56 if any portion of that member is in proper vertical relation to the screw 55. The member 56 is fastened to the lower end of a pivoted member 57, the upper end of which engages in a slide 58, the member 57 being pivoted at 59 on a part of the bracket supporting the feeding-off device. The slide 58 is normally held in the position shown in Figure 4 by a spring 60 and carries at its inner end a switch plate 61. It will be understood that the feeding-off roller 23, in its feeding-off motion, is permitted to drop into contact with the topmost sheet, and when, by reason of the successive feeding-off of the sheets, the top of the pile has fallen far enough to permit the end of the screw 55 to contact with the member 56, then the member 57 is rotated by this contact to cause the switch plate 61 to move to the right of Figure 4 to contact with the terminals 62, 63 of an electric circuit connected to any suitable source of power. Except in the instance indicated hereinafter, these terminals are connected to the solenoid 50 of the plate 421 beneath the portion of the pile with which the feeding-off roller 23 cooperates. It will be obvious, therefore, that, by reason of a valley developing in the pile at the point at which the roller 23 operates, that portion of the pile beneath the roller 23 will be raised by the closing of the circuit through the terminals 62, 63 and the solenoid 50, by the moving of the core 51 to the right of Figure 3 to turn the ratchet wheel 54 and consequently, the screw 45, to elevate the plate 421. The plate 421 is of such small area that only a small portion of the pile will be thus elevated.

It will be understood that ordinarily each of the plurality of feeding-off rollers 23 usually provided will be thus connected with a corresponding auxiliary support. If desired, however, one of these feeding-off rollers may be used to control the entire pile-elevating mechanism operated through the

usual pile-elevating devices which, in the instance shown, operate to turn the shafts 38 on either side of the pile. If desired, however, the devices just described may be used only to control the auxiliary supports under 70 each of the feeding-off rollers, in which case the entire-pile-lifting devices will be controlled by any of the well-known pile detectors cooperating with any selected portion of the pile to maintain the average height of 75 the top of the pile substantially constant.

In Figure 5 is shown a similar arrangement by which the portion of the pile beneath a separator 15 may be controlled. In this case, a switch plate 65 is attached to 80 the stem 66 of the suction separator, and a pair of terminals 67, 68 are arranged to be contacted by this switch plate when the suction separator 15, in dropping to the top of the pile, descends far enough to permit 85 the plate 65 to close the circuit through these terminals. These terminals in turn are in a power circuit connected to one of the solenoids 50 to operate one of the plates 42 beneath the portion of the pile contacted by 90 the separator 15, and that portion of the pile will be suitably elevated, as hereinbefore described, if for any reason that portion of the pile should develop a low place below the average level of the pile maintained by 95 the entire-pile-lifting devices.

As is well understood in the art, the feeding devices are driven from the press mechanism, as through the chain 70, the shaft 20 in the illustrative embodiment being turned 100 through the gears 71, 72 on the vertical shaft 73.

The operation of my novel mechanism will be obvious from the foregoing description. The sheets are piled on the board 30 105 and before the feeding is commenced, the respective portions of the top of the pile, by manipulation of the handles 55, may be brought into proper cooperative relation with the several devices constituting the 110 sheet-handling mechanism. Then, as the sheets are fed off one by one, the entire-pile-lifting device controlled either by the usual sheet detector, or by a detector connected to one of the feeding-off rollers 23, will raise 115 the entire pile from time to time to maintain the average height of the top of the pile substantially constant. If, for any reason, however, any portion beneath any one of the devices should not be lifted sufficiently to maintain the proper relation between that portion and the corresponding device, the corresponding auxiliary support 120 42 will be raised sufficiently to bring that portion of the pile to the proper height.

While I have shown an arrangement by which portions of the pile will be lifted to maintain proper working relations between each device and the pile, it will be understood that each feeding device may be ar- 125 130

ranged to be lowered or raised as the conditions may require, so as to maintain the proper working relation, and I do not wish to be limited to the specific arrangement which I have illustrated.

- 5 While I have shown the auxiliary supports as small rigid plates, it may be desirable for some purposes, particularly so as not to form a too decided bend in the paper, 70
10 to make these supports of thin flexible plates which will yield at their outer edges to conform to the curvature of the paper. It will be also understood that as many of these auxiliary supports may be provided as desired, and that their shape and size may also be varied within wide limits. They should, however, be such that, when raised, they will affect less than half of the area of the pile; otherwise, it would be possible that the 75
15 portion of the pile beneath another of the operating devices would be affected in addition to the portion beneath the device which is out of proper working relation.

It will also be understood that the main 25 platform on which the entire pile is supported may be of any suitable construction, and that the arrangement of board and channels which I have shown, is merely illustrative. While, for most purposes, I provide a board or its equivalent which is capable of supporting the entire pile, it will be obvious that a sufficient number of the small supports may be provided to support the entire pile,

30 35 While, preferably, I connect the mechanism for raising the auxiliary supports to the platform which supports the entire pile, it will be understood that, if desired, such mechanism may be located in the base of the machine so as to be entirely independent of the pile platform.

While, preferably, I employ auxiliary supports that are movable vertically, it is obvious that similar results may be obtained 45 by providing supports, such as wedges which may be moved laterally to give a lifting component to the portion of the pile under which they are inserted and I do not wish to be limited to the vertically movable supports which are my preferred form.

50 55 Although I have illustrated and described a particular kind of suction separator and a particular kind of pusher feeder as parts of the paper-handling mechanism, it will be understood that these are merely typical and 60 illustrative of the devices ordinarily used in removing the top sheet. In addition to such devices, buckling devices, hold-down devices and air pipes to blow air into the sides of the pile or beneath the top sheet may be and 65 are used in practice, and it will be understood that, if desired, such devices, when used, may also be arranged so that the relation between any one of them and the portion of the pile with which they cooperate

may be adjusted and regulated, in the manner described for the suction separator and the feeding-off rollers.

I claim:—

1. A sheet pile carrier, means to lift said carrier bodily and a support beneath the pile movable independently of said carrier and adapted to lift less than half of the area of the pile to any selected position either above, below, or the same as, the level of the remainder of the pile and hold the same in such selected position.

2. A sheet pile carrier including a movable support adapted to lift less than half of the area of the pile, means to lift the entire pile carrier and means to move said support relatively to said carrier to lift a portion only of the pile and to hold such portion in selected position.

3. A substantially horizontal sheet pile carrier adapted to support a pile of sheets arranged one over the other so that the edges of the pile are substantially vertical, said carrier comprising a plurality of supports independently adjustable vertically and each adapted to lift less than half of the area of the pile.

4. A substantially horizontal sheet pile carrier adapted to support a pile of sheets arranged one over the other so that the edges of the pile are substantially vertical, said carrier comprising a plurality of supports independently adjustable vertically and each adapted to lift less than half of the area of the pile, and mechanism adapted to move each support independently of the others.

5. A sheet pile carrier comprising a plurality of independently adjustable supports, each adapted to lift less than half of the area of the pile, and automatic mechanism constructed and arranged to move each support independently of the others to maintain the level of the pile over each support at a predetermined height.

6. A sheet pile carrier comprising a plurality of independently adjustable supports, each adapted to lift less than half of the area of the pile, automatic mechanism constructed and arranged to move each support independently of the others to maintain the level of the pile over each support at a predetermined height, and hand operable mechanism whereby each support may be adjusted independently of said automatic mechanism.

7. A sheet pile carrier comprising a plurality of independently adjustable supports, each adapted to lift less than half of the area of the pile, mechanism adapted to move each support independently of the others, and means to move all of said supports simultaneously.

8. A sheet pile carrier comprising a platform adapted to support the entire pile

means to lift said platform bodily and a support on said platform movable relatively thereto and adapted to lift positively less than half of the area of the pile.

5 9. A sheet pile carrier comprising a platform adapted to support the entire pile means to lift the platform bodily and a support on said platform and movable relatively thereto and adapted to lift less than half of 70 the area of the pile, and mechanism on said platform to move said support positively.

10 10. A sheet pile carrier comprising a platform adapted to support the entire pile and a support on said platform and movable relatively thereto and adapted to lift positively less than half of the area of the pile, and mechanism to lift said platform. 75

11 11. A sheet pile carrier comprising a board adapted to support the entire pile 80 means to lift the board bodily and an auxiliary pile support having an area less than that of said board and movable independently thereof to control the level of the top of the pile, positively said support being 85 located within the area of said board. 90

12 12. A sheet pile carrier comprising a board adapted to support the entire pile means to lift the board bodily and an auxiliary pile support having an area less than that of 95 said board and movable independently thereof and located within the area of said board, and mechanism adapted to move said support positively. 100

13 13. A sheet pile carrier comprising a board adapted to support the entire pile and an auxiliary pile support having an area less than that of said board and movable independently thereof and located within the area of said board, supports for said board 105 means to lift said supports bodily and mechanism on said supports and adapted to move said auxiliary pile support positively. 110

14 14. Sheet-handling mechanism, comprising a plurality of devices operating on different portions of the top of a pile of sheets, means to adjust the vertical operative relation between the operative portion of each of said devices and the portion of the pile with which it cooperates, independently of 115 the relation between any of the others of said devices and their respective portions of the pile, and automatic means to maintain such adjusted relation. 120

15 15. Sheet-handling mechanism, comprising a plurality of devices operating on different portions of the top of a pile of sheets, and means to maintain a predetermined vertical operative relation between the operative portion of each of said devices and the portion of the top of the pile with which it cooperates, as the sheets are removed from 125 the pile. 130

16 16. Sheet-handling mechanism, comprising a plurality of devices operating on different portions of the top of a pile of sheets,

and automatic means to maintain a predetermined vertical operative relation between the operative portion of each of said devices and the portion of the top of the pile with which it cooperates, as the sheets are removed from the pile. 70

17. Sheet-handling mechanism, comprising a plurality of devices operating on different portions of the top of a pile of sheets, and means to maintain the average level of 75 the top of the pile at a predetermined height and also a predetermined vertical operative relation between the operative portion of each of said devices and the portion of the top of the pile with which it cooperates, as 80 the sheets are removed from the pile. 85

18. Sheet-handling mechanism, comprising a plurality of devices operating on different portions of the top of a pile of sheets, and automatic means to maintain the average level of the top of the pile at a predetermined height and also a predetermined vertical operative relation between the operative portion of each of said devices and the portion of the top of the pile with which it 90 cooperates, as the sheets are removed from the pile. 95

19. A sheet pile carrier including a vertically movable support adapted to lift less than half of the area of the pile, means to remove the sheets one at a time from the top of the pile, comprising devices adapted to cooperate with different portions of the topmost sheet, means to lift the entire pile to maintain a predetermined operative relation between a portion of the top of the pile and the operative portion of one of said devices, and means to lift said support independently of said carrier to maintain a predetermined operative relation between another portion of the top of the pile and the operative portion of another of said devices. 100

20. A sheet pile carrier, means including a plurality of devices operating on different portions of the topmost sheet, to remove the 110 sheets one at a time from the top of a pile on the carrier, means to lift the entire pile to maintain the average level of the top of the pile at a predetermined height as the sheets are removed and means to lift the portion of 115 the pile beneath one of said devices to maintain the top of said portion in a predetermined operative relation to the operative portion of said device, said last-named means operating independently of said entire-pile-lifting means. 120

21. A sheet pile carrier, automatic means including a plurality of devices operating on different portions of the topmost sheet to remove the sheets one at a time from the top 125 of a pile on the carrier, means to lift the entire pile to maintain the average level of the top of the pile at a predetermined height as the sheets are removed and automatic means to lift the portion of the pile beneath one of 130

said devices to maintain the top of said portion in a predetermined operative relation to the operative portion of said device, said last-named means operating independently of 5 said entire-pile-lifting means.

22. Sheet-handling mechanism, comprising a plurality of devices operating on different portions of the top of a pile of sheets, a plurality of independent supports each 10 located beneath the pile and beneath one of said devices, and means to lift each of said supports to maintain each portion of the pile in a predetermined operative relation with the operative portion of the device cooperat- 15 ing with such portion of the pile.

23. Sheet-handling mechanism, comprising a plurality of devices operating on different portions of the top of a pile of sheets, a plurality of independent supports each 20 located beneath the pile and beneath one of said devices, and automatic means to lift each of said supports to maintain each portion of the pile in a predetermined operative relation with the operative portion of the de- 25 vice cooperating with such portion of the pile.

24. A sheet pile carrier comprising a platform adapted to support the entire pile and a support on said platform and vertically 30 movable relatively thereto and adapted to lift less than half of the area of the pile, a sheet-handling device above the pile and over said support, and automatic means to move said support to maintain a predetermined opera- 35 tive relation between the operative portion of said device and the portion of the pile with which it cooperates.

25. A sheet pile carrier comprising a platform adapted to support the entire pile and 40 a support on said platform and vertically movable relatively thereto and adapted to lift less than half of the area of the pile, a sheet-handling device above the pile and over said support, electrically operable mecha- 45 nism on said platform adapted to move said support, a switch adapted to be closed when the distance between the operative portion of said device and the portion of the pile exceeds a predetermined amount and a circuit 50 including said switch and said mechanism.

26. A sheet pile carrier comprising a plu-

rality of independent vertically movable supports each adapted to support less than half of the area of the pile, sheet-handling mechanism above the pile and adapted to remove 55 sheets one by one therefrom, said mechanism comprising a plurality of devices each ar- ranged to cooperate with a limited portion of the top of the pile above one of said supports and means to move each of said devices 60 and the support beneath it relatively to maintain in a predetermined operative vertical relation the operative portion of each of said devices and the portion of the pile with 65 which it cooperates.

27. A sheet pile carrier comprising a plurality of independent vertically movable supports each adapted to support less than half of the area of the pile, sheet-handling mechanism above the pile and adapted to remove sheets one by one therefrom, said mechanism comprising a plurality of devices each arranged to cooperate with a limited portion of the top of the pile above one of said supports and automatic means to move 70 each of said devices and the support beneath it relatively to maintain in a predetermined operative vertical relation the operative portion of each of said devices and the portion 75 of the pile with which it cooperates.

28. A sheet pile carrier comprising a plurality of independent vertically movable supports each adapted to support less than half of the area of the pile, sheet-handling mechanism above the pile and adapted to remove 85 sheets one by one therefrom, said mechanism comprising a plurality of devices each ar- ranged to cooperate with a limited portion of the top of the pile above one of said supports and means to move each of said devices 90 and the support beneath it relatively to maintain in a predetermined operative vertical relation the operative portion of each of said devices and the portion of the pile with 95 which it cooperates, said means including an electric circuit and a switch adapted to close said circuit when the distance between the device and the portion of the pile with which it cooperates exceeds a predetermined distance.

JOSEPH WHITE,
